UNITED STATES PATENT OFFICE.

ANDREW A. RITTENHOUSE, OF PITTSTOWN, NEW JERSEY.

ENVELOP.

SPECIFICATION forming part of Letters Patent No. 717,279, dated December 30, 1902.

Application filed March 1, 1902. Serial No. 96,302. (No model.)

To all whom it may concern:

Be it known that I, ANDREW A. RITTENHOUSE, a citizen of the United States, residing at Pittstown, in the county of Hunterdon 5 and State of New Jersey, have invented certain new and useful Improvements in Envelopes; and I do hereby declare the following to be a full, clear, and exact description of the invention, such as will enable others skilled in the art to which it appertains to make and use the same.

The purpose of the present invention is to guard against the surreptitious opening of letters without rendering detection possible, 15 the envelop being doubly sealed by means of an inner and an outer flap.

For a full description of the invention and the merits thereof and also to acquire a knowledge of the details of construction of the 20 means for effecting the result reference is to be had to the following description and drawings by the same reference characters.

While the essential and characteristic features of the invention are susceptible of modification, still the preferred embodiment of the 25 invention is illustrated in the accompanying drawings, in which—

Figure 1 is a detail view of the blank from which the envelop is formed. Fig. 2 is a perspective view showing the end flaps and the back partly folded. Fig. 3 is a perspective view of the envelop as seen from the rear side, the outer sealing-flap being extended and the inner sealing-flap folded. Fig. 4 is 35 a view similar to Fig. 3 as seen from the front, the parts being in the same relation and the front of the envelop having a portion broken away. Fig. 5 is a central transverse section. Fig. 6 is a central longitudinal section.

Corresponding and like parts are referred to in the following description and indicated in all the views of the drawings by the same reference characters.

The envelop comprises a front 1, back 2, 45 end flaps 3 and 4, an inner sealing-flap 5, and an outer sealing-flap 6, the several parts being adapted to fold upon the dotted lines indicated in Fig. 1. The outer sealing-flap 6 is gummed upon its inner or rear side along 50 its three edges. The back 2 is gummed upon its inner side at each end. The inner sealing-

flap 5 is gummed along its outer edge, so that when folded between the front and back the gummed side will lie against the front 1 and when moistened will become attached thereto. One of the end flaps, as 4, is gummed upon its inner side to secure said flaps when folded. The front 1 and back 2 are of like size and are preferably of rectangular shape. The end flaps 3 and 4 are of tapering form. 60 The sealing-flaps 5 and 6 may be of any configuration, and, as shown, the outer sealing-flap is preferably larger than the inner sealing-flap.

In the construction of the envelop the end 65 flaps 3 and 4 are folded upon the front 1, and their end portions are secured in the usual way. The back 2 is then folded upon the end flaps and is gummed thereto at its ends. The envelop is now ready for use, and after 70 a letter has been placed therein the flap 5 is folded so as to come between the front and back and extend over the letter or contents of the envelop and is gummed to the front 1, thereby completely sealing the envelop. For 75 additional security the outer sealing-flap 6 is folded over the back 2 and is gummed thereto, thereby increasing and adding to the difficulty of opening the envelop without rendering detection possible. 80

Having thus described the invention, what is claimed as new is—

An envelop formed from a single blank having the form substantially as shown and comprising a front, flaps at the ends of the front 85 and of a length to fold thereon and having their terminal portions overlapped and gummed, a back adapted to fold upon the end flaps and gummed at its ends thereto, a sealing-flap at the free edge of the back to 90 fold into the space between the front and end flaps and adapted to be gummed to the said front, and a second sealing-flap at the free edge of the front to fold over the back and adapted to be gummed thereto, substantially 95 as specified.

In testimony whereof I affix my signature in presence of two witnesses.

ANDREW A. RITTENHOUSE. [L.S.]
